UNITED STATES PATENT OFFICE.

CLINTON O. HARRINGTON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

REMOTE-CONTROL MEANS.

1,298,700.

Specification of Letters Patent.

Patented Apr. 1, 1919.

Application filed September 11, 1915. Serial No. 50,183.

To all whom it may concern:

Be it known that I, CLINTON O. HARRINGTON, a citizen of the United States, residing at Edgewood Borough, in the county of Allegheny and State of Pennsylvania, have invented certain new and useful Improvements in Remote-Control Means, of which the following is a specification.

My invention relates to remote control means; more particularly it relates to means for controlling a plurality of signals or other devices from one location.

I will describe my invention as applied to the voltage control of lamps used for signal lights in a railway signaling system. It is readily understood that in that branch of railway signaling where light signals are used to give both day and night indications, it is necessary to use very intense lights to make the signal indications conspicuous in daylight. It is undesirable, however, to use such intense lights for night indications on account of the excessive glare caused by strong beams of light in dark surroundings.

In present practice electric incandescent lamps are used in conjunction with lenses and reflectors to produce beams of light of the necessary intensity for daylight indications. To make these signals adaptable for night use it is desirable to reduce the voltage applied to the lamps. In standard practice the signal lamps are supplied with current from a transmission line which also supplies current to the track circuits, relays, and other apparatus along the road-bed, all of which require a practically constant voltage. For that reason it is not feasible to raise or lower the transmission voltage according to the time of day in order to intensify or weaken the brilliancy of the signal lights.

Consequently, it becomes necessary either to supply the signal lights from a separate transmission line, the voltage of which may be varied at will, or else to feed the lamps from the transmission line through a transformer having a plurality of taps which are selected to cause the lamps to burn at one intensity or another. For long stretches of track it is desirable for cheapness of operation that the switching of the signal lamps from one tap of the so-called lighting transformer to another be controlled by a simple manipulation at a central point such as a power plant or substation. One feature of

my invention is the provision of means for accomplishing this control without the use of additional line wires. In the application of my invention to a railway signal system, I provide for each signal a control device which is not operated at the ordinary line voltage, but is operated when the line voltage is changed for a small time interval by an amount greater than that caused by ordinary voltage fluctuations. The control device changes the connection of the signal lights from one tap on the lighting transformer to another and thus changes the voltage impressed on the lights in response to the temporary change of voltage of the transmission line. The other apparatus connected to the line is not affected by the temporary voltage change, which need last but several seconds.

I shall describe one form and arrangement of apparatus embodying my invention and shall then point out the novel features thereof in claims.

The accompanying drawing is a view showing a railway signaling system having applied thereto one form of apparatus embodying my invention.

Referring to the drawing I have here shown a transmission line L supplied with alternating current from a generator G. The transmission line extends parallel to a railroad track T, the rails of which are divided into a number of block sections B by means of insulated joints 1. I have shown in the drawing only one such block section. At the entrance to block B is stationed a railway signal S which I have here shown to be of the colored light signal type, in that the signal is provided with a green lamp g and a red lamp r to indicate "proceed" and "stop" respectively. It is understood, however, that I do not limit myself to this particular kind of signal.

Signal S is controlled by means of a track circuit which includes a source of potential at one end of block B, the track rails, and a relay R at the other end of the block. As here shown the source of potential is a transformer 2, the primary of which is supplied with current from line L. The relay R I have here shown to be of the two element type, in that it comprises two windings a and b, the former of which is connected directly across the track rails of

block B and the latter of which is connected to the secondary winding *c* of a transformer 3 which has its primary connected to line L. Relay R operates a contact finger 4 for 5 the purpose of controlling the indication circuits for signal S as I shall describe hereinafter.

Adjacent relay R is located an electromagnet M which is connected directly 10 across secondary *c* of transformer 3 so that magnet M is energized as long as generator G supplies current to line L. At the normal voltage of the transmission line the amount of current flowing through the 15 winding of electromagnet M is not sufficient, however, to cause it to attract its armature 5, which then rests against stop 35. Neither will magnet M be sufficiently energized to attract its armature if the transmission line 20 voltage rises within ordinary limits of voltage fluctuation met in commercial practice. If, however, the transmission line voltage is raised, say, by twice the ordinary increase due to line voltage variation above normal, 25 magnet M is energized sufficiently to attract its armature. For example if the normal voltage of the transmission line is 2200 volts, and if the voltage variation at the location at magnet M is within 5% plus or 30 minus, in other words, if the voltage is regulated not to rise 110 volts above normal under ordinary circumstances, in that case magnet M is so adjusted as not to attract its armature until the voltage is raised 35 say, 10% or 220 volts above normal. To cause such a rise in line voltage I have shown for purpose of illustration an adjustable impedance I connected in series between the generator and the transmission 40 line. It is well known that as the value of the impedance I is lowered, the voltage of the line is raised and vice versa. It is understood, however, that any suitable means may be used to effect such a rise in 45 line voltage.

When magnet M closes its armature 5, it operates a ratchet 8 through the medium of an arm 6 riveted at one end to armature 5 and a pawl 7 pivoted at the other end of 50 the arm. Pawl 7 is free to turn in a counter-clockwise direction only, so that, when it engages one of the teeth of ratchet 8 as magnet M attracts its armature, it causes ratchet 8 to turn clockwise through the distance of 55 one tooth; but when magnet M is deenergized sufficiently to release armature 5, pawl 7 turns as it engages the back of a ratchet tooth, leaving ratchet 8 in the position it last occupied. Pawl 7 is then in the position 60 to engage the next ratchet tooth when magnet M is reenergized sufficiently to again close its armature.

Ratchet 8 operates a contact finger 9 through the medium of a plurality of insulated studs 11 mounted on the ratchet 65

wheel adjacent alternate teeth and at equal distances from the center. Contact finger 9 is pivotally mounted and biased by a spring 12 to engage studs 11. When ratchet 8 is so turned that one of the studs is directly 70 above the center of the ratchet wheel, contact finger 9 is held upwardly by the stud to engage an upper stationary contact point 14. When, however, ratchet 8 is turned through the distance of one tooth, contact 75 finger 9 engages a lower stationary contact point 15. It follows that by successive operations of the armature of magnet M, contact finger 9 is caused to close alternately contacts 14 and 15.

The circuits for the lamps of signal S are controlled jointly by relay R and contact 9. When relay R is closed as shown, and arm 9 is up as shown, the circuit for green lamp *g* of signal S is as follows: from secondary 80 *d* of transformer 3 through wire 21, green lamp *g*, wire 22, contact 23—4 of relay R, wire 25, contact finger 9, contact 14 and wire 26 to winding *d* of transformer 3. Suppose now that the voltage of line L is raised sufficiently to cause magnet M to operate its armature 5. Ratchet 8 is turned as hereinbefore described through the distance of one tooth and allows finger 9 to engage lower contact 15, so that the circuit for 90 lamp *g* is the same as traced above up to and including contact finger 9 then through contact 15 and wire 27 to winding *e* of transformer 3. Since secondary windings *d* and *e* of transformer 3 are connected in 100 series, the voltage across windings *d* and *e* is higher than the voltage across winding *d* alone. As a result, lamp *g* will burn with greater brilliancy. When the voltage of line L is reduced to normal, magnet M releases its armature but ratchet 8 does not move, so that lamp *g* continues to burn at its high intensity.

If now the voltage of line L is again raised above its normal value, magnet M again 110 attracts its armature and causes ratchet 8 to advance another tooth. One of the studs 11 is thereby brought directly beneath the center of the wheel and moves contact finger 9 into engagement with the upper contact point 14. In this manner, winding *e* is open-circuited, so that signal S is again supplied by current of lower voltage and gives, therefore, a light of lower brilliancy. When the transmission line voltage is restored to normal, magnet M again releases its armature, but ratchet 8 remains in its last position and the light from signal S remains at the lower intensity.

The circuit for red lamp *r* of signal S is 125 similarly controlled by contact arm 9 and differs only from the circuit for lamp *g* in so far as it is controlled by lower contact 24 of relay R instead of upper contact 23. The circuit for red lamp *r* in detail is: from 130

winding *d* of transformer 3, through wire 21, red lamp *r* of signal S, wire 29, contact 24—4 of relay R, then through wire 25 and contact finger 9 to winding *d* or *e* of transformer 3, as the case may be. The red light, can, therefore, also be made to burn at the lower or the higher intensity.

The selection between the red lamp and the green lamp of signal S is automatically effected by means of trains on track T, as is familiar to those versed in the art of railway signaling. When there is no train in block B, current flows from transformer 2 through the track rails and energizes winding *a* of relay R, which in conjunction with winding *b* causes finger 4 to engage contact 23, thereby closing the circuit for green lamp *g*. When a train enters block B at signal S, the train wheels and axles form a low resistance shunt around relay winding *a* which is deenergized and causes contact finger 4 to engage contact point 24, to which position it is biased by gravity. In this manner the red lamp is caused to burn as long as the train remains in block B. When the train leaves the block, current from transformer 2 again flows through winding *a* of relay R so that the relay again closes contact 23—4 and the green lamp *g* is again displayed.

In the application of my invention to a railway signaling system which comprises a plurality of blocks such as described, the transmission line voltage is regulated, as is common practice, not to vary at any point, say, 5% above or below normal. During the night the signal lamps are burned at their lower brilliancy, contact 9 at each signal location then being in the position shown on the drawing. In the morning when the sky gradually becomes brighter and the signal lights begin to fade against the illuminated surroundings, the station operator raises the voltage of the transmission line 10% to 15% above normal for a few seconds, time enough to allow magnet M at each signal to operate contact 9 to the lower position at which the high voltage circuit for the lamps is closed, so that they are brightly illuminated. The lamps are changed back to the lower voltage circuit in the evening by a similar temporary raise of the voltage of the transmission line. On foggy nights the lights may be allowed to remain on the higher voltage circuit.

Although I have herein shown and described only one form of apparatus embodying my invention, it is understood that various changes and modifications may be made therein within the scope of the appended claims without departing from the spirit and scope of my invention.

Having thus described my invention, what I claim is:

65 1. In combination, a constant voltage

transmission line, a track circuit fed from said line, means for temporarily changing the voltage of said line by an amount not interfering with the proper functioning of said track circuit, means controlled by said change of voltage, and a signal controlled by said last-mentioned means and by said track circuit.

2. In combination, a constant voltage transmission line subject to normal voltage fluctuations, a track circuit fed from said line, means for temporarily changing the voltage of the line to a greater extent than caused by said fluctuations but to an extent not interfering with the proper functioning of said track circuit, means fed from said line responsive to said temporary change in line voltage but not affected by said normal voltage fluctuations, and a signal controlled by said last-mentioned means and by said track circuit.

3. In combination, a signal comprising an electric lamp, a transmission line subject to usual voltage fluctuations, means for supplying current to said lamp at one voltage for daylight indications and at a lower voltage for illumination at reduced intensity during darkness, means responsive to temporary abnormal variations in the voltage on said line but not to the usual voltage fluctuations for governing said current supplying means, and means for causing temporary abnormal variations in the voltage on said line.

4. A railway signaling system comprising a transmission line subject to the usual voltage variations, a track circuit energized from said line, means for temporarily causing an abnormal variation of the voltage on said line said temporary abnormal variation being insufficient to interfere with the operation of said track circuit, means responsive to said abnormal variation but not to the usual variations of voltage on said line, and a signal controlled by said track circuit and by said last-mentioned means.

5. In combination, a track circuit, a track relay controlled by said circuit, a source of current, a substantially constant voltage transmission line for connecting said source to said track circuit, means for at times changing the line voltage, an electromagnet connected to said line and actuated by said change of line voltage, a pawl operated by said electromagnet, a ratchet adapted to be turned by each operation of said pawl, a contact finger, means for operating said contact finger by said ratchet to occupy alternate positions at alternate operations of said ratchet, a signal, and signal circuits controlled by said alternate positions of said finger and by said track relay.

6. In combination, a track circuit, a track relay controlled by said circuit, a source of current, a substantially constant voltage

transmission line for connecting said source to said track circuit, means for at times changing the line voltage, an electromagnet connected to said line and actuated by said 5 change of line voltage, a pawl operated by said electromagnet, a ratchet adapted to be advanced by each operation of said pawl, contacts, a contact finger biased to engage one contact, means for operating said finger 10 to engage another contact at alternate advancements of the ratchet, circuits controlled by said finger and said track relay, and a signal controlled by said circuits.

7. In combination, a transmission line 15 subject to usual voltage variations, a track circuit fed from said line and including a

track relay, a railway signal comprising an electric lamp supplied with energy from said line and controlled by said relay, means for temporarily changing the voltage of said 20 line by an amount not interfering with the proper functioning of said track circuit, and a device responsive to said temporary voltage change but not to the usual voltage variations on the line for varying the voltage 25 applied to said lamp by said line.

In testimony whereof I affix my signature in presence of two witnesses.

CLINTON O. HARRINGTON.
